SCREW FEEDER AND HOLDER

William T. H. Ayers, Indianapolis, Ind.

Application April 4, 1951, Serial No. 219,300

5 Claims. (Cl. 1—49.8)

1

This invention relates to a mechanism for holding a quantity of screws, such as wood screws, and feeding one screw at a time out into a position where it may be struck with a hammer to start it in the wood, or into such position where a screw-driver or like instrument may be applied to the screw, with the primary purpose of automatically feeding the screws into the position without having to handle the screws by hand individually.

The invention lends itself to a structure which may be formed in a relatively light assembly at a comparatively low cost of production, and which will be durable over a long period of time.

A further important object of the invention resides in the extreme simplicity of the mechanism embodying the invention and in its simple movement and control.

These and many other objects and advantages of the invention will become apparent to those versed in the art in the following description of one particular form of the invention as illustrated in the accompanying drawings, in which:

Fig. 1 is a view in side elevation and partial section of a structure embodying the invention;

Fig. 2 is a like view in side elevation and partial section showing the mechanism in an operated condition;

Fig. 3 is a view in front end elevation;

Fig. 4 is a view in bottom plan on an enlarged scale;

Fig. 5 is a view in horizontal longitudinal section on the line 5—5 in Fig. 1 also on an enlarged scale;

Fig. 6 is a view in horizontal longitudinal section on the line 6—6 in Fig. 1 on an enlarged scale;

Fig. 7 is a view in top plan of a device for loading screws into the dispensing mechanism;

Fig. 8 is a view in side elevation of the loader mechanism in partial section;

Fig. 9 is a view in transverse section on the line 9—9 in Fig. 8;

Fig. 10, a modified form of screw fingers, in section on the line 5—5 in Fig. 1; and

Fig. 11, the modified form, in section on the line 6—6 in Fig. 1.

A body 10 is formed to have a vertically disposed bore 11 therethrough at its forward end portion. A boss 12 extends upwardly from the body 10 to have a continuation of the bore 11 extend therethrough and communicate with a tube 13 which is supported by and extends vertically upwardly from the boss 12.

Back of the boss 12, there is a pedestal 14 ex- 55

2

tending upwardly from the body 10. On the top side of this pedestal 14 there is fixed the forward end of a plate 15 which extends relatively horizontally therefrom to the rear and above the body 10. A handle 16 is fixed on the rear end of the plate 15.

A pair of horizontally spaced apart slide rods 17 and 18 are slidably carried by the body 10 to be free to slide in a fore and aft manner through the body 10 in an upper portion thereof. The rear ends of these rods 17 and 18 are fixed in a head 19 behind the body 10. The forward ends of these same rods 17 and 18 are tied together to carry a cross head 20 on the forward side of the body 10.

There are a pair of small rods, wire-like in nature 21 and 22 fixed to the cross head 20 to extend rearwardly therefrom in parallel relation and spaced apart a distance which will cause them to have a spacing therebetween less than the diameter of the bore 11. These two wires 21 and 22 enter and slide freely within passages 23 and 24 provided in the body 10 above the rods 17 and 18. This spacing apart of the wires 21 and 22 is made to be such that it will be slightly greater than the over-all diameter of the screw shank, but less in diameter than the head of the screw, whereby a screw may hang between the wires to be supported thereby by its head resting on the wires. This is indicated in Fig. 1.

The head 19 carries a pair of horizontally spaced apart rods or wires 25 and 26, Fig. 6, to extend slidably into bores 27 and 28 extending entirely through the body 10 in a fore and aft direction, these bores 27 and 28 intersecting the vertical bore 11 so that the wires will be maintained in a horizontally spaced apart distance equal to less than the diameter of the bore 11, this spacing being such as will permit the shank of a screw to extend therebetween, but will prevent the head of the screw from passing therebetween.

As indicated in Figs. 5 and 6 particularly, the wires 21 and 22 are carried within their respective bores 23 and 24 to have their terminal ends spaced inwardly from the back end of the body 10 when the cross head 20 is in contact with the front face of the body 10. With the same position of the cross head 20, the wires 25 and 26 are entered in their respective bores 27 and 28 a distance by their front ends 25a and 26a greater than is the spacing of the ends 21a and 22a of the wires 21 and 22 from the back face of the body 10. In other words the ends of these respec-

3

tive wires 21, 22, and 25, 26 are in vertically disposed and spaced apart overlapping relations. It is to be noted that the bores 27 and 28 are located in spaced relation below the bores 23 and 24, Figs. 1 and 2, a distance somewhat less than the over-all length of the screws from their pointed ends to the undersides of their heads.

Normally the head 19 is held in its rearmost position of travel as limited by the striking of the cross head 20 against the front of the body 10. This positioning of the head 19 in its rearmost position is set up by reason of the compression spring 29 which bears between the back side of the body 10 and the front side of the head 19. The spring 29 is maintained in place by having a push rod 30 extend axially therethrough from a fixed end connection with the head 19 to enter slidingly through a lower portion of the body 10, Figs. 1 and 2. This push rod 30 is centered to travel diametrically across under the lower side of the body 10 centered on the axis of the bore 11. A pair of spring members 31 and 32 are fixed by rear ends in the body 10 to extend downwardly and thence forwardly on each side of the path of the push rod 30 to terminate at a distance in front of the body 10. Preferably the front ends of these members 31 and 32 are formed as indicated in Fig. 4 to grip around the shank of a screw 33. Normally the members 31 and 32 tend to spring into contact by their forward ends one with the other. As indicated in Figs. 1 and 2, the spaced apart members 31 and 32 extend horizontally from the body 10, and are spaced below the orifice of the bore 11 a distance sufficient to permit clearance of the head of a screw to pass across under the body 10 after it has emerged from the bore 11 and is hanging on these two members 31 and 32 by its head. The spacing apart of these members 31 and 32 is made to be less than the diameter of the bore 11, and such that the shank of the screw 33 may freely enter therebetween, but the head 34 will rest and be carried by these spaced apart members. The push rod 30 is in the path of the head 34 as it travels between the members 31 and 32.

There is a bracket 35 mounted on the plate 15 to revolutely support a cross shaft 36. On the right-hand side of the bracket 35 and fixed to this cross shaft 36 is an operating lever 37 conveniently located in reference to the handle 16 so that the operator gripping the handle 16 may use his thumb to push downwardly on this handle 37. On the other end of the shaft 16 there is fixed a depending lever 38 which has a nose 39 to come into the path of the head 19 therebelow. The lever 39 travels through a slot 40 provided in the plate 15.

To operate the mechanism so far described, there is a loading device provided as illustrated in Figs. 7-9, wherein there is a box 41 having a floor 42 thereacross, and through which floor there extends longitudinally a central slot 43 just wide enough to permit the shanks of the screws 33 to drop through that slot, and have the heads 34 suspended on the floor 42 on either side of the slot. Screws 33 are dumped into the box 41 and the box is shaken or agitated to cause screws 33 to enter by their shank ends through the slot 43 and be arranged in parallel, vertically disposed alignment with the heads 34 uppermost.

At one end of the slot 43, herein shown at the left end, there is a vertically disposed tube 44 having an inside diameter such that it may receive the top end of the tube 13 on the position-

4

ing or dispensing mechanism. This tube 44 is notched as at 45 to permit the screws 33 to slide down the slot 43 when the box 41 is inclined by its right-hand end so that the screws 33 will come into the upper end of the tube 44 in substantially axial alignment with that tube 44 to have their shank ends pointed downwardly, whereby the screws will feed through the tube 44 one after another with the heads uppermost.

By means of the loader device thus described, screws 33 are put into the tube 13 of the dispenser device until the desired number are carried therein. With the tube 13 filled with screws, the lowermost screw 33a, Fig. 1, will be supported between the upper wires 21 and 22.

The lever 37 is depressed to push the head 19 forwardly into contact with the back side of the body 10 to bring the mechanism into that condition as shown in Fig. 2. In this travel of the head 19 forwardly, the wires 21 and 22 are withdrawn from their normal positions across the bore 11 as indicated in Fig. 5, whereupon the screw 33a is no longer supported thereby, but the wires 25 and 26 have been carried across the bore 11, by reason of their overlapping end relations, so that these wires 25 and 26 are presented across the bore 11 before the wires 21 and 22 are withdrawn therefrom. Then the lower screw 33a is permitted to drop down to that position as indicated in Fig. 2 where that screw is supported then by the lower set of wires 25 and 26. A screw 33b is resting on the head of the screw 33a.

When the lever 37 is released to be carried back upwardly by reason of the return action of the compression spring 29, the wires 25 and 26 are withdrawn from their positions across the bore 11 which permits the screw 33a to drop downwardly between the lower wires 31 and 32 where again the screw is supported by its head to hang therebetween. When these wires 25 and 26 are withdrawn from across the bore 11, the upper wires 21 and 22 travel across the bore 11, their ends 21a and 22a being carried entirely across the bore 11 before the wires 25 and 26 are withdrawn therefrom. This means that these wires 21 and 22 have passed, one on each side, across the outer sides of the shank of the screw 33b so that when the screw 33a drops downwardly, the screw 33b then drops down to be supported by its head on the wires 21 and 22.

A subsequent action follows in that the lever 37 is pressed downwardly again to repeat the operations above indicated, with the further operation of the push rod 30 then pushing the screw 33a forwardly along between the wires 31 and 32 to carry the screw then to the outer position as indicated by the screw 33, Fig. 2. Releasing the lever 37 permits the push rod 30 to return to its normal position as indicated in Fig. 1, whereby the screw 33 is then left in the position as shown in Fig. 2. The cross head 20 is likewise back into its normal position in contact with the front side of the body 10 so that the screw 33 is in an outer, exposed condition where it may be operated upon either by driving it into wood by means of a hammer or by starting to turn it by means of a screw driver. The handle 16 is employed to guide the entire device about so that the screw 33 is located on the work in the desired position.

To facilitate the locating of the screws 33 on the work (not shown) and to prevent the screws 33 from being accidentally knocked out of its gripping position between the wires 31 and 32, a guide 47 is provided in the nature of a V-like

piece of metal having its ends fixed to the sides of the body 10 to extend by a central portion 48 below the lowermost point of the screw 33. That is, the entire dispensing device may be guided by its handle 16 to rest the lower end 48 of the guide 47 on the work, so that it may be tilted or rocked around to bring the screw 33 at the exact location desired.

The device is shown in that arrangement of the operating lever 37 whereby the handle 16 is to be gripped by the left hand of the operator so that he may hold the hammer or screw-driver as he would normally in his right hand.

Referring to the slightly modified form shown in Figs. 10 and 11, plates 50 and 51 are substituted for the wires 21, 22 and 25, 26 respectively, these plates being bifurcated to have the spaced fingers 52, 53 on the plate 50 and 54, 55 on the plate 51. That is, these fingers in each instance operate to intercept the screws 33 in the two-step operation of dropping one screw at a time to the lower wire or fingers 31 and 32. These plates 50 and 51 with their respective fingers are reciprocated in the slots 56 and 57, being secured to the heads 20 and 19 respectively. The ends of the fingers 52, 53 are in vertically spaced apart overlapping arrangement with the lower fingers 54, 55, conforming to the same arrangement as described in relation to the wires 21, 22 and 31, 32.

For the purpose of definition, it is intended that the terms "wires" as applied to the wires 21, 22 and 31, 32 be interchangeable with the term "fingers" carrying the reference numerals 52, 53 and 54, 55. In either form the members serve in effect as fingers regardless of their cross-section shape and of how they are mounted.

While I have herein shown and described my invention in the one form which I have found to be very effective, it is obvious that structural changes may be employed without departing from the spirit of the invention, and I therefore do not desire to be limited to that precise form beyond the limitations which may be imposed by the following claims.

I claim:

1. A screw dispensing device comprising a body having a passageway normally vertically disposed confining screws to end to head abutment and down which the screws may slide to a lower discharge end; a pair of spaced apart fingers having free ends shiftable across said passageway, the spacing of the fingers being less than the diameter of the heads of said screws and sufficient to allow the screw shanks to enter freely therebetween; a second pair of fingers shiftable across said passageway at a zone below said first fingers, the second pair of fingers having free ends shiftable across said passageway and being spaced apart a distance less than the diameter of said screws but sufficient to allow the shanks of the screws to enter freely therebetween; a third pair of fingers extending from said body in fixed positions by one set of free ends, below said discharge end of the passageway, spaced apart one from the other horizontally less than the diameter of the heads of said screws, but sufficient to allow the shanks of the screws to enter freely therebetween; a push rod reciprocable between said first and second pairs of fingers; means maintaining said first and second pairs of fingers to have opposing ends in vertically disposed overlapping arrangement to have the end portions of one pair enter said passageway before the end portions of the other pair leave that passageway; and means shifting said first and second finger pairs and

5 pairs and said push rod in unison in the order of said first pair of fingers being moved to have their ends withdrawn from said passageway after said second pair of fingers enter by their ends and traverse the passageway, and said push rod travels between said third pair of fingers away from said discharge end; said maintaining means comprising a crosshead to which said first pair of fingers are fixed by outer end portions, a head to which said second pair of fingers are fixed by their outer end portions, said crosshead and said head being on opposite sides of said body, and said fingers being slidably guided in said body, and rigid tie means between and spacing apart said crosshead and said head.

2. A screw dispensing device comprising a body having a passageway normally vertically disposed confining screws to end to head abutment and down which the screws may slide to a lower discharge end; a pair of spaced apart fingers having free ends shiftable across said passageway, the spacing of the fingers being less than the diameter of the heads of said screws and sufficient to allow the screw shanks to enter freely therebetween; a second pair of fingers shiftable across said passageway at a zone below said first fingers, the second pair of fingers having free ends shiftable across said passageway and being spaced apart a distance less than the diameter of said screws but sufficient to allow the shanks of the screws to enter freely therebetween; a third pair of fingers extending from said body in fixed positions by one set of free ends, below said discharge end of the passageway, spaced apart one from the other horizontally less than the diameter of the heads of said screws, but sufficient to allow the shanks of the screws to enter freely therebetween; a push rod reciprocable between said third pair of fingers; means maintaining said first and second pairs of fingers to have opposing ends in vertically disposed overlapping arrangement to have the end portions of one pair enter said passageway before the end portions of the other pair leave that passageway; and means shifting said first and second finger pairs and said push rod in unison in the order of said first pair of fingers being moved to have their ends withdrawn from said passageway after said second pair of fingers enter by their ends and traverse the passageway, and said push rod travels between said third pair of fingers away from said discharge end; said maintaining means comprising a crosshead to which said first pair of fingers are fixed by outer end portions; a head to which said second pair of fingers are fixed by their outer end portions; said crosshead and said head being on opposite sides of said body; and said fingers being slidably guided in said body; and rigid tie means between and spacing apart said crosshead and said head; said push rod being carried by said head; and means normally maintaining said head spaced from said body to position said first pair of fingers across said passageway and withhold the second pair from thereacross.

3. A screw dispensing device comprising a body having a passageway normally vertically disposed confining screws to end to head abutment and down which the screws may slide to a lower discharge end; a pair of spaced apart fingers having free ends shiftable across said passageway, the spacing of the fingers being less than the diameter of the heads of said screws and sufficient to allow the screw shanks to enter freely therebetween; a second pair of fingers shiftable across said passageway at a zone below said first

5 fingers; the second pair of fingers having free ends shiftable across said passageway and being spaced apart a distance less than the diameter of said screws but sufficient to allow the shanks of the screws to enter freely therebetween; a third pair of fingers extending from said body in fixed positions by one set of free ends below said discharge end of the passageway, spaced apart one from the other horizontally less than the diameter of the heads of said screws, but sufficient to allow the shanks of the screws to enter freely therebetween; a push rod reciprocable between said third pair of fingers; means maintaining said first and second pairs of fingers to have opposing ends in vertically disposed overlapping arrangement to have the end portions of one pair enter said passageway before the end portions of the other pair leave that passageway; means carried by said body shifting said first and second finger pairs and said push rod in unison in the order of said first pair of fingers being moved to have their ends withdrawn from said passageway after said second pair of fingers enter by their ends and traverse the passageway, and said push rod travels between said third pair of fingers away from said discharge end; said maintaining means comprising a cross-head to which said first pair of fingers are fixed by outer end portions; a head to which said second pair of fingers are fixed by their outer end portions; said crosshead and said head being on opposite sides of said body; said rods being slidably guided in said body; rigid tie means between and spacing apart said crosshead and said head; said push rod being carried by said head; means normally maintaining said head spaced from said body to position said first pair of fingers across said passageway and withhold the second pair from thereacross; said shifting means comprising a handle, and a lever adjacent thereto to shift said head toward said body; said head maintaining means comprising a spring.

4. A screw dispensing device comprising a body having a passageway normally vertically disposed confining screws to end to head abutment and down which the screws may slide to a lower discharge end; a pair of spaced apart fingers having free ends shiftable across said passageway, the spacing of the fingers being less than the diameter of the heads of said screws and sufficient to allow the screw shanks to enter freely therebetween; a second pair of fingers shiftable across said passageway at a zone below said first fingers, the second pair of fingers having free ends shiftable across said passageway and being spaced apart a distance less than the diameter of said screws but sufficient to allow the shanks of the screws to enter freely therebetween; a third pair of fingers extending from said body in fixed positions by one set of free ends, below said discharge end of the passageway, spaced apart one from the other horizontally less than the diameter of the heads of said screws, but sufficient to allow the shanks of the screws to enter freely therebetween; a push rod reciprocable between said third pair of fingers; means maintaining said first and second pairs of fingers to have opposing ends in vertically dis-

10 posed overlapping arrangement to have the end portions of one pair enter said passageway before the end portions of the other pair leave that passageway; means interengaging in fixed manner said first and second pairs of fingers and said push rod as a shiftable unit; and means carried by said body shifting the unit of said first and second finger pairs and said push rod in unison in the order of said first pair of fingers being moved to have their ends withdrawn from said passageway after said second pair of fingers enter by their ends and traverse the passageway, and said push rod travels between said third pair of fingers away from said discharge end; said passageway consisting of a relatively vertically disposed bore through said body, and a screw storage tube having a discharge end aligned with said bore and carried by said body.

5. A screw dispenser device comprising a body having a screw passageway normally vertically disposed and confining screws to passage therethrough in end to head relation; a pair of horizontally laterally spaced apart fingers having free ends shiftable across said passageway; a second pair of horizontally laterally spaced fingers having free ends shiftable across said passageway in vertically spaced and overlapping relation to said first pair of fingers, the second pair of fingers being directed oppositely to the first pair; a cross head on each side of said body, one head having the first pair of fingers secured thereto, and the other head having the second pair of fingers secured thereto; a member spaced from said screw passageway secured to and extending between said cross heads; a third set of horizontally and laterally spaced apart fingers carried by said body, extending across and spaced below the lower end of said screw passageway, to terminate at a distance laterally beyond said body; a push rod slidably guided by the body to travel between the fingers of said third pair; all of said pairs having their fingers horizontally and laterally spaced for receiving the shanks of the screws therebetween and the heads resting across the fingers; the fingers of said first and second pairs having lengths extending from their respective cross heads such that the ends of fingers in one pair of traverse said passageway to have finger portions extend thereacross prior to the withdrawal from the passageway of the finger ends of the other pair; and a member interconnecting one of said cross heads with said push rod causing said first and second pairs of fingers and said push rod to move in unison when said push rod is reciprocated.

WILLIAM T. H. AYERS.
